(57) **CLAIM**

The ornamental design for a repeater for communications apparatus, as shown and described.

DESCRIPTION

FIG. 1 is a top, front and right side perspective view of a repeater for communications apparatus showing our new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of the repeater for communications apparatus shown within the area designated as 9 in FIG. 4.

The broken lines in the drawings are for the purpose of illustrating portions of the repeater for communications apparatus that form no part of the claimed design. The dot-dashed broken lines in FIGS. 4 and 9 show the boundary of the enlarged view and form no part of the claimed design.
